Att.

UNITED STATES PATENT OFFICE.

WILLIAM M. AUSTIN, OF AMESBURY, MASSACHUSETTS, ASSIGNOR TO J. B. JUDKINS COMPANY, OF MERRIMAC, MASSACHUSETTS, A CORPORATION OF MASSACHUSETTS.

DOOR PILLAR.

Application filed June 3, 1924. Serial No. 717,493.

To all whom it may concern:

Be it known that I, WILLIAM M. AUSTIN, a citizen of the United States, a resident of Amesbury, in the county of Essex and Commonwealth of Massachusetts, have invented an Improvement in Door Pillars, of which the following is a specification.

In the construction of bodies of certain vehicles and more particularly of closed body automobiles, it is common, in many types of bodies, to have the lower portion of the sides of the body curved inwardly as they extend downward. This involves a corresponding formation of the lower portion of the doors, which, in such constructions, usually curve inwardly from a point adjacent the middle thereof, the curvature usually being most pronounced in the lowest portion thereof. These doors usually have inner and outer sides providing an intermediate space for the sliding window glass, and are constructed on a frame, the upright portions of which are termed pillars, one of which is provided at each vertical edge. When the doors are curved inward, as above described, these pillars are usually sawed from whole stock, and not bent, to the exact curvature desired. It has been found that for some reason or reasons, the curved portion, even though not bent from its original formation, after it has been in use for a few months usually begins to straighten, so that the upper and lower portions of the door swing outward with relation to the middle portion thereof, with the result that when the door is closed, the outer surface of its upper and lower portions will not be flush with the outer surface of the adjacent portion of the body, as it was when originally constructed. This result is highly objectionable from the standpoint, at least, of appearance, and for other reasons, and moreover the door does not tightly close at the bottom. Whether this change in formation is due to something inherent in the wood, or to the blows which are more or less constantly sustained by the lower edge of the door in striking against the sill or door jamb, when the door is closed, or to both, or whether it is due to some other cause, I am not aware, but the fact remains that it is a matter of frequent occurrence, and while I have, prior to my present invention, made various attempts to overcome this difficulty, as by securing suitably shaped

metal reinforcing strips to the sides of the pillar, I was not able to obviate the difficulty satisfactorily. Moreover, the use of metal reinforcing strips on either the exterior or interior sides of the pillar is objectionable or impractical for several reasons, as they would interfere with the attachment of the panels or lining of the door, as the case may be, and aside from being expensive, if made of sufficiently heavy material to be reasonably effective, the increased weight would be an objection.

The primary object of my invention is to provide means for overcoming or counteracting the straightening effect above described on strips of wood which have been sawed into curved form, and to do this without adding materially to the cost of construction and without substantial change in the material of which the parts are constructed.

I accomplish these objects by forming in the convex side of a strip of wood which has previously been cut out in curved form, an elongated recess of uniform depth, which extends the entire width of the strip, so as to provide two oppositely facing, transversely disposed abutments or shoulders at the ends of the recess, and by providing a flexible wooden brace which is of the same width and thickness as the width and depth of the recess, but is of slightly greater length, then placing the brace in the recess with its ends abutting against said shoulders and its middle portion sprung outward from the recess bottom, and then forcing the middle portion of the brace against the bottom of the recess, so that its ends will be pressed against said shoulders with sufficient force to cause a strong thrust action to be exerted against the ends of the fibers of the wood which terminate in said shoulders, the brace being permanently secured in this position, so that the thrust action thus secured will be constantly maintained and the straightening action above referred to will be prevented.

For a more complete understanding of my invention, reference is made to the accompanying drawing in which:

Fig. 1 is a side elevation of a portion of an automobile body in which my invention is embodied.

Fig. 2 is an edge view of one of the doors.

Fig. 3 is a front edge view, on a larger scale of a portion of a door pillar.

Fig. 4 is a side view thereof.

Fig. 5 is a detail view of the brace.

Fig. 6 is a front edge view of the door pillar portion with the brace in position for 5 attachment.

Fig. 7 is a similar view showing the brace secured in position.

While my improved construction may be variously employed to advantage in various 10 relations, particularly in connection with various parts of automobile bodies, I have herein illustrated it in connection with the lower portion of the door pillar of a closed automobile body, in which connection the 15 use thereof is more advantageous than any other relation of which I am at present aware.

In the construction of such doors, an upright pillar *a* is provided at both front and 20 rear edges thereof, to which the outer panels and inner linings are secured, and in constructing these pillars, they are sawed, in approximately the form shown, from wood, the grain of which preferably runs as nearly 25 longitudinally of the piece as is practicable, as indicated by the double pointed arrow in Fig. 2. As thus formed, the pillar extends into a gradual curve, from the middle portion, as it extends downward, the portion of 30 greatest curvature being intermediate the lower portion of the pillar.

To embody my invention in the door pillar *a*, I first remove, or saw out, a portion of the wood of the pillar, from the convex side 35 thereof, to a uniform depth in the instance shown, to approximately one-fourth its thickness, so as to form a recess *a'* therein which extends transversely of the pillar from one side to the other and longitudinally, in the instance shown, throughout its 40 middle portion for approximately one-third the total length, so that a substantial portion of the recess extends over the lower curved end portion of the pillar, to, or nearly to the point of greatest curvature. The recess terminates in approximately square shoulders *a²*, *a³*, or shoulders which are approximately at right angles to the adjacent outer 45 surface. These shoulders may be, and preferably are slightly undercut, but should not be beveled. I further provide a brace piece 50 *b* which is of the same width and thickness as the width and depth respectively of the recessed portion of the pillar, but is of slightly 55 greater length. The angular relation of the under side of the brace *b* and its end faces are also the same as that of the bottom and ends of the recess. The brace is preferably, but not necessarily, made of wood of 60 somewhat greater hardness than the wood of which the pillar is formed. It must also be slightly resilient or flexible with the grain 65 of the wood running longitudinally. It is also provided with a series of screw holes *b'*, arranged at suitable intervals in the mid-

dle line thereof throughout practically its entire length.

In carrying out my process, the brace *b* is placed in the recess *a'* with its end faces in abutment with the shoulders *a²*, *a³*, and, to 70 do this, the brace is sprung slightly into bowed form, as shown in Fig. 6. A series of ordinary wood screws *c* are then inserted in the middle holes *b'* of the brace and screwed into the pillar until their heads are engaged with the brace and then they are forced in still further so as to draw in its middle portion until its inner side is firmly seated against the bottom of the recess, as shown in Fig. 7, screws nearer the ends of the brace 75 then being also preferably inserted and tightened. As the brace is longer than the distance between the shoulders *a²*, *a³*, the result is that as its middle portion is drawn inward, its end faces are forced against said shoulders with considerable force, a strong 80 leverage action being thus secured. This force is not sufficient to increase the curvature, or otherwise distort the pillar, but is sufficient to cause substantial compression of the fibers adjacent the shoulders or thrust force thereon, and at the same time the pillar is practically restored to its original condition, as the recess which was formed therein is refilled with wood.

The strong end thrust on the shoulder *a³*, which is located in the curved portion of 95 the pillar, completely counteracts the tendency of the curved portion of the pillar to straighten either from strain on its lower end, or from any other causes, so that the original shape in which the pillar was formed will be retained.

It will be understood that the above described method of preventing distortion or 100 bending of strips of wood may be variously applied in other relations, as conditions may require. It is, however, particularly advantageous when used in the relation above indicated, as previously explained.

I claim:

1. In combination with a strip of wood, having a longitudinally extending recess in one side providing remotely located, transversely disposed shoulders at its ends, 115 arranged to face toward each other, a flexible wooden brace shaped correspondingly to said recess and of normally greater length than the distance between said shoulders, said brace having its ends engaged with said shoulders and its middle portion sprung into engagement with the bottom of said recess to cause a strong end thrust thereon said shoulders, and means for 120 permanently securing said brace in said position to hold said strip against lateral deflection to the side on which said brace is located.

2. A strip of wood having a portion 125 thereof provided with a convex surface

and having a recess therein extending from a point in said surface for a substantial portion of the length of the strip, said recess having a transversely disposed shoulder at each end, a flexible wooden brace normally of slightly greater length than the distance between said shoulders and otherwise corresponding in shape to said recess, and means for forcing the end faces of said brace against said shoulders by forcing the middle portion of said brace against the bottom of said recess, and for permanently securing the brace in said position to provide a permanently acting thrust against said shoulders.

5

3. A strip of wood cut into a form to provide a convexly shaped surface portion and having a recess therein extending from a point in said surface throughout the width thereof and longitudinally of the

20

strip at a uniform depth for a substantial portion of the length and providing at each end a transversely disposed shoulder, a wooden brace of equal width and thickness to the width and depth of said recess and having end faces corresponding to said shoulders, the normal distance between which is slightly greater than the distance between said shoulders, and means for holding said end faces in engagement with 25 said shoulders and for forcing the intermediate portions of the brace against the bottom of the recess, said means being adapted to hold the brace permanently in this position to provide a constantly acting 30 thrust action on said shoulders.

35

In testimony whereof, I have signed my name to this specification.

WILLIAM M. AUSTIN.
